UNITED STATES PATENT OFFICE

WALTER BRUHN, OF ST. LOUIS, MISSOURI, ASSIGNOR, BY MESNE ASSIGNMENTS, TO
REMINGTON RAND INC., OF NEW YORK, N. Y., A CORPORATION OF DELAWARE

ACCOUNTING METHOD AND APPARATUS

Application filed January 19, 1920. Serial No. 352,602.

This invention relates to a method and apparatus for the finding of accounts.

In an accounting apparatus and system, such as described in Letters Patent No. 5 1,615,806, granted to L. A. Watters et al. January 25, 1927, the account cards are arranged in a tray or trays. Where the numerical or decimal system is used, the tray is arranged to receive one thousand cards, and accordingly, 10 the assembled cards are divided into ten groups of one hundred cards each, each group is divided into divisions or units of ten cards each, and each division or unit comprises ten cards. The tray is divided by partitions into 15 one hundred compartments, each of which contains a unit or division of ten cards.

Arranged below the tray is selecting mechanism, comprising, a series of ten pairs of selectors, that is, one pair for each ten compartments. These selectors are mounted on a carrier which is arranged for movement along the tray so that each pair of selectors is adapted to be located in alinement with any one of its corresponding ten compartments. The selectors are mounted for vertical movements so as to enter the compartments and an actuator is provided for thus moving these selectors. However, these selectors are normally disconnected from a main actuator, 25 but any desired pair of selectors is arranged to be selectively clutched with the actuator so as to render a selected pair effective for actuation. Mounted also on the carrier are audit selectors which bridge the main selectors, and these audit selectors are arranged to be interconnected with the main selectors so as to form together selector bars arranged 30 along the tray.

The selector carriers are mounted on a 40 carriage which is expansible transversely so as to adjustably position the carriers transversely to any selected position, and stop mechanism is provided for effecting transverse location of the carriers and the selectors 45 thereon.

The cards are provided along their lower edges with selective characteristics which are variably positioned along the bottom edges to correspond to the different positions 50 of the cards in a compartment. Accordingly,

the characteristics of corresponding cards in the different compartments occupy corresponding transverse positions so that the characteristics of corresponding cards will be in line longitudinally of the tray. Accordingly, after the connection of the selected pair of selectors with the actuator, and after positioning of the selector carrier to aline the connected selectors with the desired compartment, the transverse positioning of the 55 selectors will cause the same to be alined with the characteristics of the desired card, so that upon elevation of the connected selectors by the actuator, the desired card will be raised above the remaining cards in the tray. Also 60 upon interconnection with the main selectors of the audit selectors, the transverse positioning of the carrier and elevation of the now interconnected selectors will cause corresponding cards in each compartment to 65 be elevated.

In order to permit replacement of a desired card there is provided in the apparatus of the patent referred to a pilot for each compartment; this pilot is elevated upon actuation of the selectors when set to elevate the desired card in the compartment in which the card is to be replaced, in order that the compartment can be readily found. Accordingly in the apparatus of said patent, such 75 pilots are necessary in order to permit replacement of a card. Such pilot does not, however, fix definitely the location with respect to the remaining cards in the compartment at which the withdrawn card should be 80 replaced, but it only locates the compartment in which it is to be replaced.

One of the objects of this invention, therefore, is to provide a method and apparatus, whereby the compartment in which the withdrawn card is to be replaced is not only located, but also its position in the compartment is definitely located and ascertained.

Another object is to provide a method and apparatus whereby the location of the compartment of a withdrawn card will concurrently elevate the adjacent or next card so as to definitely locate the position where the withdrawn card is to be replaced.

Another object is to provide an account 100

card having characteristics corresponding not only to its own position but also to the position of the next adjacent card.

Further objects will appear from the detail description taken in connection with the accompanying drawings, in which:

Figure 1 is a view showing the bottom edges of a unit of cards and the characteristics thereon;

Figure 2 is a similar view showing the cards assembled;

Figure 3 is a transverse section of a tray showing the cards therein and showing also the selectors; and

Figure 4 is a detail longitudinal section of a machine showing more particularly the construction of the tray and of the selectors.

In the specification and claims, the term "card" is used in its broadest sense, so as to include ordinary cards, loose-leaves, sheets, or other accounting elements used in the keeping of accounts. The term "tray" is also used in its broadest sense so as to include holders, racks, etc., adapted for the holding and segregating of accounts.

In the description of the invention reference is had to the patent referred to for a full and detail explanation of the machine or apparatus to which this invention is more particularly applicable, and in these drawings similar parts are indicated by like reference characteristics as in said patent.

Referring more particularly to Figures 3 and 4, 6 designates a part of the frame of the machine, 10 the encasing sides of the tray and 11 the forward end connecting the sides, there being a similar rear end 11, both of which are connected by the sides 10. Side plates 12 connect the sides and ends so as to form ledges. Arranged inside of the encasing sides 10 are side walls 13 of the tray proper which flare upwardly and are secured to the ledges 12 so as to form therewith rests for supporting the cards as hereinafter described, but leave the bottom of the tray open.

Arranged transversely of the tray are a series of strips 15 which are supported on the ledges and on a longitudinal strip 14 connecting the ends 11. The strips 15 in this case are extended upwardly so as to form partitions. The strips 15 are toothed as shown at 21 so as to form flaring guides for the selectors S as hereinafter described, there being a series of ten flared notches on each side of the median line of the tray. These flared notches, therefore, guide the selectors into the bottom of the tray.

The selectors S are mounted to slide vertically on carriers 45, there being two carrier side bars extending longitudinally of the tray and these carrier side bars are mounted to slide on the carriage side bars 30, each of which has a cross-head 31 mounted for movement transversely of the tray rolling on and between rods 33 and 35, these carriage side

bars being interconnected so as to move transversely but remain parallel. The carrier side bars 45 are provided with heads 51 connected with shanks 52.

The position of the carriage transversely of the tray is controlled by a series of stops so as to position the selectors in variant positions transversely of the tray. Moreover the carrier is positioned longitudinally of the tray by a series of variantly positioned stops. The stops are controlled by selective manipulative elements or keys on a key board.

The shanks 52 have each connected therewith but so as to permit rotation with respect thereto, an actuator shaft 63 which is arranged for rocking movement and supported in and movable with the carrier. This actuator shaft has splined thereon a series of clutches, each clutch 65 having a perforated arm or jaw 66 adapted to engage with a lug or tooth 67 on the selector. The clutch is connected with a bell crank lever 93-96 mounted on a stationary bracket 91 and connected by a link with an actuator element arranged to be operated by a spring 97 when one of the keys on the key board is actuated.

A retainer 71 holds the clutch in either engaged or disengaged position. There are a series of these clutches one for each actuator.

Mounted on a side bar 60 on a carrier and on which the selectors S are also mounted are a series of audit selectors 62 which bridge the main selectors S and which are connected at their lower ends. Slidably mounted on each side bar 60 is a connecting element 282 which has a number of hooks 283 arranged to engage with pins on the selectors S when the element is moved to the right, Figure 4, by the cross bar 280 on arms 279, actuated by the audit key on the key board.

Referring now to Figures 1 and 2, C designates cards which are arranged in a unit of ten and are provided with selective characteristics L arranged variantly along the bottom edge of each card, and corresponding respectively in their positions to the positions of the cards in the unit. The selective characteristics are duplicated on opposite sides of the median line so that a pair is concurrently engageable by a pair of selectors.

The parts so far described are as shown and described in the patent referred to, to which reference is had for details of construction. However, a brief summary of the operations will be given.

Suppose that it is desired to find card number "122". The auditor will successively depress the keys "1", "2", "2". The depression of the primary key "1" will engage the second clutch, as shown in Figure 4, thereby rendering the "1" selectors effective for actuation but leaving all of the other selectors S disconnected. Upon depression of the secondary key "2" carrier 45 will move rearwardly until the connected selectors are directly under-

neath the "20" division of the second group. Upon depression of the tertiary key "2", the carriage 30 will move outwardly so as to move the selectors S outwardly from dotted to full position, Figure 3, so as to align the selectors with the characteristics L on the "2" card. Thereafter the actuators 63 will elevate the selectors causing them to be guided by the guide notches 21 into engagement with the 10 characteristics L, so as to elevate the card number "122", leaving all of the other cards undisturbed.

In accordance with this invention, in addition to the main characteristics L, each 15 card is also provided with supplementary characteristics M. This supplementary characteristic is so arranged that it will correspond in position to the characteristics of the adjacent card, or as in the specific embodiment shown, the card of the next higher member in the unit. Thus the "2" card will have in addition to its main characteristic, a supplemental characteristic corresponding in position to the main characteristic of the "1" 25 card. Similarly the "3" card will have in addition to its main characteristic, a supplementary characteristic corresponding to the "2" card. It is, of course, understood that the supplementary characteristic as well as the 30 main characteristic is duplicated on opposite sides of the median line of the card. It will also be noted that the supplemental characteristic has a vertical depth or extent less than the main characteristic, that is, it is 35 shorter and provides a space vertically between the bottom edge of the main characteristic and the bottom edge of the supplementary characteristic.

It will, therefore be seen that when the 40 selectors are aligned with the main characteristics on any given card, such as card "122", they will also align with the supplementary characteristics on the next succeeding card, namely "123". Accordingly when the 45 selectors are elevated, they will not only engage the main characteristics on card "122", but also the supplementary characteristics on card "123", and accordingly both of these cards will be elevated. In view of the fact that the 50 supplementary characteristics are shorter or of less extent than the main characteristics, there is a lost motion between the selectors and the supplementary characteristics after the main characteristics are engaged. Accordingly, while both cards are raised, the 55 desired card "122" is raised full height, while the next succeeding card "123" is only raised partially. Accordingly, upon complete isolation, the desired card "122" will project beyond the next succeeding card "123" as fully shown in Figure 3. The face of the card "122" will, therefore be fully shown, while the succeeding card "123" will be invisible. 60 The desired card "122" can, however, readily

be picked out on account of its projection beyond the next succeeding card, "123".

The invention is of great utility in a card finding system. Thus, after the card has been found, isolated and withdrawn, it can be readily replaced, as its position is indicated by the next succeeding card, which remains isolated, or which can be isolated by setting on the key board the number of the withdrawn card. Accordingly, the withdrawn card can readily 70 be replaced not only in its compartment, but also in its correct position, as this correct position is immediately in front of the partially isolated card, which is partially raised when the number of the desired card is set up 75 on the key board. Accordingly, the cards can be kept in numerical order, even in a compartment, without any additional labor or expense.

The invention is also of utility in the auditing of accounts. When auditing an account, the audit selectors 62 are interconnected with the main selectors S by movement to the right of the bars 282 upon depression of the audit key. When, therefore, after depression of 80 the audit key, any given key, such as "2" is depressed thereby causing the main and audit selectors to be positioned opposite the selective characteristics on all cards ending in "2", upon elevation of the main and audit selectors all cards ending in "2" will be elevated, that is, all corresponding accounts will be located and isolated, as described in the patent referred to. This will, however, cause location and isolation of all accounts next to and succeeding those corresponding accounts. Now if any card is missing its number will be definitely indicated by the partial elevation of the next succeeding card in the division of the misplaced or lost card, and the finding thereof and its replacement in proper position is 90 facilitated.

It will moreover be noted that this invention entirely dispenses with the necessity of pilots.

It is obvious that various changes may be made in the details without departing from the spirit of this invention; it is, therefore, to be understood that this invention is not to be limited to the specific details shown and described.

Having thus described this invention what is claimed is:

1. The method of finding accounts mechanically, comprising, locating the desired account and dependently the one next thereto.
2. The method of finding accounts mechanically, comprising, locating the desired account and dependently the succeeding account.
3. The method of finding accounts mechanically, comprising locating and isolating the desired account and dependently the one next thereto.
4. The method of finding accounts me- 130

- chanically, comprising, locating the desired account and dependently the one next thereto, and displacing the located accounts to different extents.
5. The method of finding accounts mechanically, comprising, locating the desired account and dependently the one next thereto, and displacing both accounts, the desired account to a greater extent than the one next thereto.
10. The method of finding accounts mechanically, comprising, locating in a unit division of accounts a desired account together and dependently with another account in that unit.
15. The method of finding accounts mechanically, comprising, locating and isolating in a unit division of accounts a desired account together and dependently with another account in that unit.
20. The method of finding accounts mechanically, comprising, locating the unit division of accounts containing the desired account, and locating in that unit the desired account together and dependently with another account in that unit.
25. The method of finding accounts mechanically, comprising, locating the unit division of accounts containing the desired account, and locating and isolating in that unit the desired account together and dependently with another account in that unit.
30. The method of finding accounts mechanically, comprising, locating the unit division of accounts containing the desired account, and locating in that unit the desired account together and dependently with the account next to the desired account.
35. The method of finding accounts mechanically, comprising, locating the unit division of accounts containing the desired account, locating in that unit the desired account together and dependently with another account in that unit, and displacing the located accounts to different extents.
40. The method of finding accounts mechanically, comprising, locating the unit division of accounts containing the desired account, locating in that unit the desired account together and dependently with the succeeding account.
45. The method of finding accounts mechanically, comprising, locating the unit division of accounts containing the desired account, locating in that unit the desired account together and dependently with the succeeding account, and displacing both accounts, the desired account to a greater extent than the succeeding one.
50. The method of finding accounts mechanically comprising, locating the group containing the desired account, locating in that group the division containing the desired account, and locating in that division the desired ac-
- count and dependently the succeeding account.
55. The method of finding accounts mechanically comprising, locating the group containing the desired account, locating in that group the division containing the desired account, and locating and isolating in that division the desired account and dependently the succeeding account.
60. The method of finding accounts mechanically comprising, locating the group containing the desired account, locating in that group the division containing the desired account, and locating in that division the desired account and dependently the succeeding account.
65. The method of finding accounts mechanically comprising, locating the group containing the desired account, locating in that group the division containing the desired account, and displacing both accounts, the desired account to a different extent than the succeeding one.
70. The method of finding accounts mechanically comprising, locating the group containing the desired account, locating in that group the division containing the desired account, locating in that division the desired account and dependently the succeeding account, and displacing both accounts, the desired account to a different extent than the succeeding one.
75. The method of finding accounts mechanically comprising, locating the group containing the desired account, locating in that group the division containing the desired account, locating in that division the desired account and dependently the succeeding account, and displacing both accounts, the desired account to a different extent than the succeeding one.
80. The method of auditing accounts mechanically, comprising, locating corresponding accounts in each group of a series, and dependently accounts next to the corresponding accounts.
85. The method of auditing accounts mechanically, comprising, locating corresponding accounts in each group of a series, and dependently accounts next to the corresponding accounts, and isolating both accounts.
90. The method of auditing accounts mechanically, comprising, locating corresponding accounts in each group of a series, and dependently accounts next to the corresponding accounts, and isolating the latter accounts.
95. An account card having selector-coactable characteristics adapted upon cooperation therewith of selector means to cause displacements to different extents.
100. An account card having main and supplementary selector-coactable characteristics, the main characteristic being adapted to cause displacement to a greater extent than the supplementary characteristic.
105. An account card having main and supplementary selector-coactable characteristics, the main characteristic being of a different size from the supplementary characteristic.
110. A unit division of account cards, each card of which has a selector-coactable characteristic which defines its position in the unit and another selector-coactable characteristic which corresponds in position to the first-mentioned characteristic of another card in the unit.
115. A unit division of account cards, each card of which has a selector-coactable characteristic which defines its position in the unit and another selector-coactable characteristic which corresponds in position to the first-mentioned characteristic of the next card in the unit.
120. A unit division of account cards, each card of which has a selector-coactable characteristic which defines its position in the unit and another selector-coactable characteristic which corresponds in position to the first-mentioned characteristic of the next card in the unit.
125. A unit division of account cards, each card of which has different selector-coactable characteristics, one of which defines the position of that card in the unit and the other of which corresponds in position to the first-

mentioned characteristic of another card in the unit.

26. A unit division of account cards, each card of which has selector-coactable characteristics of different proportions, the one of greater proportion defining the position of that card in the unit and the one of lesser proportion corresponding in position to the first mentioned characteristic of the next card.

27. A unit division of account cards, each card of which has selector-coactable characteristics comprising, a main characteristic and a supplementary characteristic corresponding in position to the main characteristic of another card in that unit.

28. A unit division of account cards, each card of which has selector-coactable characteristic comprising, a main characteristic and a supplementary characteristic corresponding in position to the main characteristic of the next card in that unit.

29. A unit division of account cards, each card of which has selector-coactable characteristics comprising, a main characteristic and a supplementary characteristic of less extent than the main characteristic but corresponding in its position to the main characteristic of the next card in that unit.

30. A unit division of account cards, each card of which has selector-coactable characteristics of different extents comprising, a main characteristic and a supplementary characteristic corresponding in its position to the main characteristic of another card in that unit.

31. In a card finding and separating device, means for holding a plurality of cards in upright positions, a pair of card-lifting members for engaging and lifting each card, and means provided on each card whereby when a card is lifted by said lifting members the next adjacent card of higher denomination is also lifted.

32. In a card moving and separating device, a receptacle containing a plurality of cards, each bearing a pair of depending projections, a pair of card-moving members adapted to transverse travel beneath said cards for engagement with the pair of projections of any of said cards, and means provided on each of said cards whereby when any one of said cards is elevated by said card-moving members, the next card in order adjacent the card being moved is elevated at one end thereof.

33. In a card finding and separating device, means for holding a plurality of cards in upright positions, a pair of card-lifting members for engaging and lifting each card, and means provided on each card whereby when a card is lifted by said lifting members the next adjacent card of higher denomination is lifted therewith at one end.

34. An accounting apparatus, comprising, a tray having account cards therein, and se-

lecting means arranged to select predetermined cards, said cards having selective characteristics for cooperation with said selecting means for locating a desired card and an adjacent card.

35. An accounting apparatus, comprising, a tray having account cards therein, and selecting means arranged to select predetermined cards, said cards having selective characteristics for cooperation with said selecting means for locating a card next to the desired card, said selecting means and said characteristics cooperating for obtaining the displacement of the located cards.

36. An accounting apparatus, comprising, a tray having account cards therein, selecting means arranged to select predetermined cards, said cards having selective characteristics for cooperation with said selecting means for locating a desired card and another card next thereto, said selecting means and said characteristics cooperating for obtaining displacement of the located cards.

37. An accounting apparatus, comprising, a tray having account cards therein, selecting means arranged to select predetermined cards, said cards having selective characteristics for cooperation with said selecting means for locating a desired card and another card next thereto and for displacing both cards, the desired card to a greater extent than the next card.

38. An accounting apparatus, comprising, a tray having account cards, and selecting means arranged to select predetermined cards, said cards having selective characteristics for cooperation with said selecting means for locating the positions of desired cards and the cards next thereto and displace the cards next to the positions of said desired cards.

39. An accounting apparatus, comprising, a tray having account cards, selecting means arranged to select predetermined cards, said cards having selective characteristics for cooperation with said selecting means for locating desired cards and the cards next thereto and for partially projecting the located cards from the tray, the desired cards to different extents than the cards next thereto.

In testimony whereof I affix my signature this 7th day of November, 1919.
